UNITED STATES PATENT OFFICE.

HENRI DIAMANTI AND NICOLAS BEUF, OF BEAULIEU, FRANCE.

HYDRO-EXTRACTOR.

No. 905,297.

Specification of Letters Patent.

Patented Dec. 1, 1908.

Application filed June 25, 1907. Serial No. 380,760.

To all whom it may concern:

Be it known that we, HENRI DIAMANTI and NICOLAS BEUF, citizens of the Republic of France, and residents of Beaulieu, France, have invented new and useful Improvements Relating to Hydro-Extractors, which improvements are fully set forth in the following specification.

The present invention has for its object 10 a hydro extractor for a continuous and adjustable output, and intended for use in the manufacture of artificial silk and generally speaking in other industries such as sugar factories, refineries, etc.

15 In order that the invention may be readily and clearly understood, the hydro extractor in question is shown by way of example as applied to the manufacture of artificial silk in the accompanying drawing, in which:

20 Figure 1 represents a vertical section on the axis of the hydro extractor. Fig. 2 is a plan view. Fig. 3 shows in elevation the details of the pallets for the distribution in the basket of the material to be dried. Fig.

25 4 represents a vertical section of the upper part of the apparatus, and of the passage for the discharge of the dried material. Fig. 5 is a perspective view illustrating the knife in detail. Fig. 6 is a diagrammatic 30 view of the knife projected onto a vertical plane.

The hydro extractor which forms the object of the invention comprises broadly a basket *a* frusto conical in form, inverted and appropriately recessed, closed at its lower part by a frustum of a cone *b* inclined slightly to the vertical axis *c* of the apparatus.

35 The wet cotton to be dried is supplied to the basket *a* through a passage *d* arranged in the axis of the apparatus and above a distribution device *e*. Fig. 3. The distributor consists of spirally wound flanges situated at the orifice of the passage *d* and having a pitch which is hardly appreciable at their upper part, which becomes more and more rapid in proportion toward the bottom of the basket.

40 The upper part of the hydro extractor is closed by a circular cover *f* from which the passage *g* serving for the discharge of the dried material runs tangentially.

45 This special form of hydro extractor permits of an adjustable discharge of the cotton by means of a knife *h*, Figs. 2 and 5, arranged in the lower part of the passage *g*.

The cutting part *h', h''* of the knife *h* is a horizontal plane, and its lateral edges are supported by guides *i*, Fig. 5, in such a manner as to give it not only an inclination 60 in the longitudinal direction of the passage, but also in the transverse direction. This plowshare arrangement, as will readily be understood, facilitates taking up cotton and discharging it through the passage *g*. 65 The portion of the passage *g* which comes after the knife is cylindrical.

The cotton to be dried which is introduced into the apparatus through the passage *d* reaches the pallets *e* which distribute it over 70 the bottom of the apparatus.

The basket *a* rotating at a very high speed by means of an appropriate transmission which need not be further described, the cotton is forced by centrifugal force to come 75 against the wall of the cone *a* and mounts it. Another frustum of a cone *a'*, the large base of which is common with that of the cone *a*, stops the ascent of the cotton and prevents it from escaping in blocks. The cotton then 80 forms a roll such as is represented in broken lines in Fig. 1 of the accompanying drawing; this tends to mount constantly and encounters the cutting part *h', h''* of the knife. The cutting device consists of a plate *h* which 85 is adjustably borne in longitudinal guides *i* provided in the passage *g*. The cotton roll, under the influence of the impulse given to it and during the rotation of the basket, is constantly thrown against the edge *h', h''* of the 90 blade *h*, and is thereby cut and the cut off portions pass over the inclined plane of the plate *h* entering the passage *g* through which they leave the apparatus completely dry.

The output of the apparatus is regulated by 95 depressing the line *h', h''* of the knife more or less, and this is done by sliding the blade *h* in the guides *i*. The more the front edge of the knife is depressed the greater is the quantity of material removed from the roll 100 and the larger the output from the apparatus. If, on the other hand, the knife be raised, the quantity of material removed is less and the output smaller.

Having now particularly described and 105 ascertained the nature of our said invention and in what manner the same is to be performed, we declare that what we claim is:—

1. The herein described hydro-extractor for continuous and adjustable output, comprising a basket with a biconic wall and a 110 conical bottom, an axial passage projecting

into the basket and through which the material enters the latter, a distribution device at the origin of said passage, a cover for said basket, and a discharge passage tangential thereto, substantially as set forth.

2. The herein described hydro - extractor for continuous and adjustable output, comprising a basket with a biconic wall and a conical bottom, an axial passage projecting into the basket and through which the material enters the latter, a distribution device at the origin of said passage, a cover for the said basket, a discharge passage tangential thereto, and means at the origin of said passage for facilitating the discharge of the dried material through the said passage, substantially as set forth.

3. The herein described hydro - extractor for continuous and adjustable output comprising a rotary basket with a biconic wall and a conical bottom, an axial passage projecting into the basket and through which the material enters the latter, a distribution device at the origin of said passage, the said distribution device consisting of spirally wound flanges, the pitch of which becomes more and more rapid towards the bottom of the basket, a cover for the latter and a discharge passage tangential to the said cover, substantially as set forth.

4. The herein described hydro - extractor for continuous and adjustable output comprising a rotary basket with a biconic wall and a conical bottom, an axial passage projecting into the basket and through which

the material enters the latter, a distribution device at the origin of said passage, the said distribution device consisting of spirally wound flanges, the pitch of which becomes more and more rapid towards the bottom of the basket, a cover for the latter, a discharge passage tangential to the said cover, and means at the origin of said passage for facilitating the discharge of the dried material through the said passage, substantially as set forth.

5. The herein described hydro - extractor for continuous and adjustable output, comprising a rotary basket having a biconic wall and a conical bottom, an axial passage projecting into the said basket through which the material enters the latter, a distribution device at the origin of said passage, the said distribution device consisting of spirally wound flanges, the pitch of which becomes more and more rapid towards the bottom of the basket, a cover for the latter, a discharge passage tangential to the said cover and an adjustable knife in the form of a plow share at the origin of said discharge passage to facilitate the collection and discharge of the dried material, substantially as set forth.

In testimony whereof we have signed this specification in the presence of two subscribing witnesses.

HENRI DIAMANTI.
NICOLAS BEUF.
